Primary Examiner—James Gandy**Assistant Examiner**—Cathron B. Matta**Attorney, Agent, or Firm**—James H. Beusse**[57]****CLAIM**

The ornamental design for a disposable bottle cap with integrated valve for bottle pressurization, as shown and described.

DESCRIPTION

FIG. 1 is a perspective view of my new and ornamental design showing the lower portion thereof;

FIG. 2 is an elevation view of the design of FIG. 1;

FIG. 3 is a cross-sectional view, taken along line 3—3 of FIG. 4, of the design of FIG. 1;

FIG. 4 is a top plan view of the design of FIG. 1; and,

FIG. 5 is a bottom plan view of the design of FIG. 1.
